UNITED STATES PATENT OFFICE.

JULIE DESPRÉS, OF NEW YORK, N. Y.

DESIGN FOR AN ARTICLE OF MANUFACTURE.

46,863.

Specification for Design.

Patented Jan. 19, 1915.

Application filed October 12, 1914. Serial No. 866,388. Term of patent 3½ years.

To all whom it may concern:

Be it known that I, JULIE DESPRÉS, a citizen of the Republic of France, residing in the borough of Manhattan of the city of New York, in the State of New York, have invented a certain new, original, and ornamental Design for an Article of Manufacture, of which the following is a specification, reference being had to the accompanying drawing, forming a part hereof.

The drawing is a view in front elevation of the ornamental design for a decoration for souvenirs which embodies the invention.

I claim—

The ornamental design for an article of manufacture as shown.

JULIE DESPRÉS.

In the presence of—

E. M. TAYLOR,
WORTHINGTON CAMPBELL.
